SHOULDER STRAP CLIP

Ruth Freedman, New York, N. Y.

Application September 16, 1936, Serial No. 101,015

2 Claims. (Cl. 24—85)

This invention relates to shoulder strap clips, and is an improvement of the invention described in U. S. Letters Patent No. 1,505,328, dated August 19th, 1924.

5 The object of the invention is the production of a shoulder strap clip adapted to be detachably connected to the inner face of a garment, and which will detachably support the shoulder straps of under garments against slipping. The clip 10 is also adapted to detachably support means for holding in proper position various other objects.

In the accompanying drawing Fig. 1 shows an enlarged top view of an exemplification of the shoulder strap clip in its open position; Fig. 2 15 is a bottom view of Fig. 1; Fig. 3 represents a section of Fig. 1 on the line 3, 3; Fig. 4 indicates a section of Fig. 1 on the line 4, 4; and Fig. 5 shows a top view of the shoulder strap clip in its closed position connected to a garment and 20 supporting shoulder straps.

A hollow longitudinal support comprises the top wall 20, the curved side wall 21, the straight side wall 22 and the bottom wall parallel to the wall 20 comprising the members 23. The top 25 wall 20, the curved side wall 21, and one of the members 23 of the bottom wall of the support form a longitudinal clamping pocket. The said top wall 20, the straight side wall 22 and the other member 23, of the bottom wall form a 30 second longitudinal clamping pocket. The said members 23 at one end thereof are pressed against the top wall 20 as shown in Fig. 3. The said longitudinal support at one end joins with the locking housing, comprising the top wall 30 and the bottom projections 31 spaced from 35 and parallel to the said top wall 30, forming the locking pockets 32.

A fastening pin cylindrical in cross section is indicated with the outer member 35 spaced from 40 the longitudinal support and having the tapered end 36, and the inner member 37 positioned within and fastened to the said longitudinal support. The members 35 and 37 are connected by the crown 38.

45 A clamping bar square in cross section comprises the outer member 40 spaced from the longitudinal support and having the locking hook 41 at one end, and the inner member 42 located within and fastened to the longitudinal support. The members 40 and 42 are joined by the connecting cross member 43.

50 After the members 37 and 42 are positioned within the longitudinal support, pressure is brought against the top wall 20 and the members 23 of the said longitudinal support to se-

curely clamp said members 37 and 42 in said support. By this means the member 37 is somewhat flattened to securely maintain it in place.

Referring to Fig. 5 the hollow longitudinal support is again indicated with its top wall 20 and the top wall 30 of its locking housing. The outer member of the fastening pin is again shown at 35 with its tapered end 36. The outer member 5 of the clamping bar is again indicated at 40 with its locking hook 41. A fragmentary 10 portion of a lady's garment is shown in section at 50. The member 35 of the fastening pin is forced through a portion of the garment 50, and the tapered end 36 is locked to the locking housing having the top wall 30. The 15 outer member 40 of the clamping bar supports a plurality of shoulder straps 60 of under garments and the locking hook 41 of said member 40 is locked to said locking housing having the top wall 30.

20 Various modifications may be made in the invention and the present exemplification is to be taken as illustrative and not limitative thereof.

Having described my invention, I claim:

1. In a shoulder strap clip the combination of 25 a longitudinal support having longitudinal clamping pockets at the sides thereof, a locking housing at one end of the longitudinal support and having locking pockets, a fastening pin cylindrical in cross section having an outer member with a tapered end, spaced from the longitudinal support, said fastening pin also having an inner member somewhat flattened fastened in place in one of said clamping pockets of the support, the tapered end of the pin adapted to 30 be seated in one of the locking pockets of the locking housing and a clamping bar square in cross section comprising an outer member spaced 35 from the longitudinal support and having a locking hook at one end thereof, the latter adapted to be seated in the other pocket of the locking housing, said clamping bar also having an inner member fastened in place in the other longitudinal 40 clamping pocket of the support, the members 45 of the clamping bar joined by a connecting member.

2. In a shoulder strap clip the combination of 50 a longitudinal support having a top wall with side walls extending therefrom, and having a bottom wall comprising a pair of members extending from said side walls and parallel to said top wall, said top wall, side walls and the members of the bottom wall forming a pair of longitudinal 55 clamping pockets for the support, a locking housing at one end of the longitudinal

support, said locking housing having a top wall and bottom projections spaced from its top wall and parallel thereto and forming locking pockets, a fastening pin cylindrical in cross section having an outer member spaced from the longitudinal support and having a tapered end adapted to be seated in one of the pockets of the locking housing, said pin having an inner member somewhat flattened spaced from its outer member fastened in place in one of the longitudinal clamping pockets of the longitudinal support and

a clamping bar square in cross section having an outer member spaced from the longitudinal support and having a locking hook at one end thereof, the latter adapted to be seated in the other pocket of the locking housing, said clamping bar having an inner member fastened in place in the other longitudinal clamping pocket of the support, the members of said clamping bar joined by a connecting cross member.
